UNITED STATES PATENT OFFICE.

DANIEL A. B. BAILEY AND NORMAN MCGILLIVARY, OF POTSDAM, NEW YORK.

WRENCH.

SPECIFICATION forming part of Letters Patent No. 393,321, dated November 20, 1888.

Application filed May 28, 1888. Serial No. 275,332. (No model.)

To all whom it may concern:

Be it known that we, DANIEL A. B. BAILEY and NORMAN MCGILLIVARY, citizens of the United States, residing at Potsdam, in the county of St. Lawrence and State of New York, have invented certain new and useful Improvements in Pipe-Wrenches; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to pipe-wrenches; and it has for its object to provide a wrench of this kind which shall be both simple and durable, and at the same time more efficient in operation and less expensive in construction than the tools of this class that have heretofore been constructed.

To these ends, and to such others as the invention may relate, the same consists in the peculiar construction and in the novel combinations, arrangement, and adaptation of parts, all as more fully hereinafter described, shown in the drawings, and then specifically defined in the appended claims.

In the accompanying drawings, which, with the letters of reference marked thereon, form a part of this specification, Figure 1 is a perspective view of the head of a wrench constructed in accordance with my invention. Fig. 2 is a side view, partly in section. Fig. 3 is a top plan view of the same.

Reference now being had to the details of the drawings by letter, A represents the lever of the wrench, upon one end of which is formed the enlarged portion or head B, the extreme outer end of which is inclined downwardly and is provided with a chisel-shaped edge, C. Near the lower edge of the lever, and at a point near the head of the wrench, a hole, D, is provided, within which hole is secured one end of the chain E, which may be of any well-known construction.

F are lugs or ears cast integral with and forming a part of the head B. These lugs are arranged upon the upper surface of the head

of the wrench, having their bases upon the opposite outer edges of the same, and each lug is bent or inclined backward and inwardly, thus forming a dish-shaped recess or chamber, G, provided at its front and rear sides with narrow vertical slots or openings H H'.

In operation the free end of the chain E is passed around the pipe and back over the head of the wrench, and one of the links of the chain is placed horizontally within the chamber formed by the lugs upon the head of the wrench, where it will bind against the inner walls of the chamber and will be securely retained in place. The link of the chain next adjacent to the chamber upon either side will pass through the slots H H', while the link at the rear of the chamber will lie in a horizontal position across the head of the wrench and will bear against the rear faces of the lugs at the rear of the chamber. In moving the lever or handle of the wrench upward the chisel-edge C is caused to bear directly against the pipe. The strain upon the chain will be divided between the link which is retained within the chamber upon the head of the wrench and the link at the rear of the chamber.

We attach special importance to our dish-shaped chamber, within which one of the links of the chain is adapted to fit, whereby the strain is divided between the links and the walls of the chamber, and in order to the more equally divide the strain the rear edges or faces of the lugs F are made flat and vertical, as shown, so that the link of the chain adjacent to the rear of the chamber has a flat bearing against the vertical sides of the lugs, as will be readily understood.

What we claim to be new is—

1. The wrench described, consisting of the lever A, formed at one end with head B, the outer end of which is inclined downwardly and is provided with a chisel-shaped edge, C, the chain E, one end of which is secured to the head of the wrench, and the lugs F, formed of said head and constituting the walls of a dish-shaped chamber, G, provided at diametrically opposite sides in line with the lever with vertical slots, substantially as described.

2. The chain-wrench described, consisting of

the lever A, head B, provided at its end with
downwardly-inclined chisel-shaped edge C, the
chain E, the downwardly-extended lug having
a hole, D, to receive one end of the chain, and
5 the dish-shaped chamber upon the upper face
of the head of the lever over the said lug, said
chamber being adapted to receive and retain
within its walls one link of the chain and
formed by the inwardly-inclined lugs fixed on
10 said head and having vertical rear edges, sub-

stantially as shown and described, and for the
purpose specified.

In testimony whereof we affix our signatures
in presence of two witnesses.

DANIEL A. B. BAILEY.
NORMAN McGILLIVARY.
